UNITED STATES PATENT OFFICE.

CYRIL H. THOMAS, OF CHICAGO, ILLINOIS.

INSULATOR.

1,388,217.

Specification of Letters Patent. Patented Aug. 23, 1921.

Application filed May 9, 1919. Serial No. 295,849.

To all whom it may concern:

Be it known that I, CYRIL H. THOMAS, a subject of the King of Great Britain, residing at Chicago, in the county of Cook and 5 State of Illinois, have invented certain new and useful Improvements in Insulators, of which the following is a specification.

The invention relates to improvements in insulators.

10 One of the objects of the invention is to provide an improved form of insulator and support or hanger therefor, whereby to produce a stable and stanch union between the insulator and its support.

15 Another object of the invention is to provide a support for an insulator in which the clamp exerts a compressing strain on the insulating body, which is distributed over a relatively large surface of the more or less refractory material, of which the insulator 20 is usually composed.

25 And still another object of the invention is to provide an insulator hanger serving as a housing to retain the contacting portions 25 of the insulator relatively dry, when subjected to the effects of the weather.

30 While my improved insulator and hanger are not designed exclusively for out of door use, as they can conveniently and advantageously be employed for the same purpose indoors, and while it is not confined to any particular form of insulator except the portion thereof adapted for the purpose, it 35 will therefore be understood that the invention is not limited to the specific showing depicted in the drawing, but is of a scope commensurate with and limited only by the definition of the claim.

In the drawings:—

40 Figure 1 shows a central section of a fragment of an insulator with a hanger attached thereto, the section being taken on line 1—1 of Fig. 2.

Fig. 2 is a plan view of the hanger.

45 Fig. 3 is a detail of part of the angular clamping ring by which the hanger is secured to the insulating body.

In all the views the same reference characters are employed to indicate similar 50 parts.

55 5 is an insulating body, of any desired form, having an annular projecting portion 6 somewhat in the shape of an inverted cone with the apex of the cone merging into the body part of the insulator and the flat base extending therefrom. The major portion of

the hanger 7 is cup shaped, having a skirt 8 depending from a flat base having a central perforated aperture 9. The aperture affords means for the introduction of a threaded support, of any desired formation, for the purpose of supporting the insulator and hanger. The hanger is perforated at intervals, as at 10, for screws 11. A clamping ring 12 is divided into a plurality of sections, in the drawings there are shown to be two parts, 13 and 14. The members 13 and 14 are preferably of metal and contain threaded perforations 16 to receive the threaded shanks of the screws 11. The members 13 and 14 are angularly shaped in cross section, as clearly shown in Fig. 1, the inner surface corresponding in its angular relation with the outer surface of the cone portion 6 of the insulator, and the outer surface of the clamping member being substantially vertical to correspond with the inner surface of the skirt 8 of the hanger 7.

To apply the hanger to the insulator, it is necessary first to put the clamping members 13 and 14 in the positions that they occupy when the hanger is permanently located, then place the cup shaped member 7 on the outside of the clamping members and insert the screws. It is obvious, now, that when 80 the screws are tightened the ring members 13 and 14 are drawn farther into the skirt of the hanger and thereby they will firmly hold the hanger in contact with the insulator. It will be observed that the clamping 85 members 13 and 14, engage relatively large surfaces of the projection 6. The clamping members being divided into a plurality of sectors or parts, adapt themselves to the contour of the insulator and, on account of 90 the wedging action effected by the tightening of the screws there is no breaking strain imparted to the more refractory insulating material. There is no projecting attaching means, such as screws, bolts or the like, and 100 the outside contour of the hanger is round and smooth, the best shape or form to prevent brush discharge and other leakages.

The insulator may be employed for various purposes; for supporting high tension conductors, bus bars, switches, transformers, and the like, and there may be a plurality of hangers connected to or associated with a single insulator, should occasion require.

Having described my invention, what I 110 claim is:—

An insulator, and hanger therefor, said

insulator having an integral annular co-
noidal projection similar in shape to a trun-
cated cone with its base extending from the
body and its apex merging in the body there-
of, in combination with a cup-shape hanger
having a flat base part overlying the cone
base and a skirt extending over the circum-
ferential part of the cone; a split ring, an-

gular in cross-section, for insertion between
said skirt and cone, and screws passing ¹⁰ through
said base into said split ring to
wedge the latter between said skirt and cone
and to clamp the hanger to the insulator.

In testimony whereof I have hereunto sub-
scribed my name.

CYRIL H. THOMAS.
